UNITED STATES PATENT OFFICE.

CARMELINO GULFI, OF BOSTON, AND GIOVANNI LANFRANCHI, OF BEACHMONT,
MASSACHUSETTS.

CUE.

Application filed October 25, 1922. Serial No. 596,804.

To all whom it may concern:

Be it known that we, CARMELINO GULFI and GIOVANNI LANFRANCHI, citizens of the United States, residing at Boston and Beachmont, respectively, in the county of Suffolk and State of Massachusetts, have invented new and useful Improvements in Cues, of which the following is a specification.

10 This invention relates to improvements in cues, the general object of the invention being to provide spring pressed tips for the cue for absorbing shocks incident to the tips striking the balls.

15 Another object of the invention is to make the tips removable so that a new tip can be put in place when the old one has become worn.

This invention also consists in certain 20 other features of construction and in the combination and arrangement of the several parts, to be hereinafter fully described, illustrated in the accompanying drawings and specifically pointed out in the appended 25 claim.

In describing the invention in detail, reference will be had to the accompanying drawings wherein like characters denote like or corresponding parts throughout the 30 several views, and in which:—

Figure 1 is an elevation of a cue constructed in accordance with this invention.

Figure 2 is a view partly in section.

Figure 3 is a detail view of the block 35 used in this invention.

In these views 1 indicates the cue which is provided with a bore 2 in its tip end in which is slidably mounted a block 3. A spring 4 is arranged in the bore and tends

to hold the block in its outer position. The 40 block is limited in its movement by means of the screws 5 and the nuts 6 which engage notches 7 formed in the block. The outer end of the block is provided with a screw threaded hole 8 for receiving the screw 9 45 which is carried by the flanged elements 10 secured to the tip 11. Thus the tip can be removed whenever desired and a new one substituted. The spring acts as a shock absorber so as to take up the shock incident 50 to the tip striking a ball.

It is thought from the foregoing description that the advantages and novel features of the invention will be readily apparent.

We desire it to be understood that we 55 may make changes in the construction and in the combination and arrangement of the several parts, provided that such changes fall within the scope of the appended claim.

What we claim is:—

A cue having a bore in one end, a block 60 slidably mounted in said bore and being provided with diametrically oppositely arranged notches, a nut arranged in each notch, screws passing through the side walls 65 of said bore and received by the nuts for limiting the outward movement of said block, a coiled spring having its end convolutions engaging the bottom of the bore and the inner end of the block respectively 70 and a flanged element carrying a tip and being threadedly mounted in the outer end of the block for the purpose specified.

In testimony whereof we affix our signatures.

GIOVANNI LANFRANCHI.
CARMELINO GULFI.
